(57) **CLAIM**

The ornamental design for an integral display mount, as shown and described.

DESCRIPTION

FIG. 1 is a top, left, front perspective view of an integral display mount embodying our new design;

FIG. 2 is a left elevational view thereof, the right elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line representations in the views are for illustrative purposes only and form no part of the claimed design.

In a preferred embodiment, the nature of this product is an integral display mount for a material handling vehicle.

1 Claim, 6 Drawing Sheets
